UNITED STATES PATENT OFFICE.

DANIEL A. WEDMORE, OF PHILADELPHIA, PENNSYLVANIA, ASSIGNOR TO PHILADELPHIA STEEL & WIRE CO., OF PHILADELPHIA, PENNSYLVANIA, A CORPORATION OF NEW JERSEY.

SUPPORTING AND SPACING MEANS FOR REINFORCING-BARS.

1,153,279.

Specification of Letters Patent. Patented Sept. 14, 1915.

Application filed December 13, 1910. Serial No. 597,114.

To all whom it may concern:

Be it known that I, DANIEL A. WEDMORE, a citizen of the United States, residing in Philadelphia, Pennsylvania, have invented 5 certain improvements in Supporting and Spacing Means for Reinforcing-Bars, of which the following is a specification.

My invention relates to reinforced concrete construction, and the object of my invention is to provide means for spacing and supporting reinforcing bars disposed within or upon centering prior to the pouring of the concrete. These and other features of my invention are more fully set forth hereinafter, reference being had to the accompanying drawings, in which:

Figure 1, is a view in elevation of one form of spacing device embodying my invention, and Fig. 2, is a perspective view of 20 the same.

It is desirable, in the use of reinforcing bars in concrete construction, to support and space the same at substantially definite and regular intervals in order that full advantage may be taken of the amount of reinforcing material used, and in order further that there need be no excess of metal and that all parts of the concrete shall be reinforced to the same extent.

30 In my improved structure I preferably provide means for maintaining the reinforcing bars at definitely spaced points; the structure being organized when assembled for this purpose. In other instances the spacing and supporting means may be adjustable relatively to each other, if desired, so that changes in the position or width of separation between the rods may be accomplished when placing the same on the job, 45 if desired. Generally, however, it is preferred that the supporting and spacing means be definitely placed.

In the drawings, 1 represents a supporting element or carrier which may be a metal bar round, square, or any other shape convenient for use, and carried by this bar are the metal chairs 2, which may be of sheet metal as shown in the drawings, shaped to receive the reinforcing bars 3, indicated by 50 dotted lines. The chairs may be definitely positioned with respect to the bar 1 by upsetting portions of the latter, as indicated at the points 4. These chairs may consist of a strip of sheet metal bent by suitable means

and having substantially the shape of the 55 letter M or an inverted W in cross section, with a plurality of legs 5 for engagement with the centering; the legs 5 being connected by a web 6 below the bar 1. The legs 5 as well as the walls of the web 6 are apertured at 60 7 for the passage of the bar 1. It will be understood, of course, that the upsetting of the bar 1 as indicated at 4 is accomplished after the chairs have been strung upon the 65 same.

It may be desirable to take advantage of the springy nature of this chair to maintain the same substantially at any point along the rod; the upper portions above the bar 1 having a tendency to grip the reinforcing 70 rod supported by the same. I prefer, however, to upset the metal of the bar 1 to hold the chairs in position and definitely space the same. This is substantially a necessity, since the supporting and spacing means are 75 handled roughly; being generally thrown upon the job, and the chairs must maintain their place upon the rods 1. I do not wish, however, to be limited to this construction.

The chair forming the subject of my invention is particularly sturdy, since its shape and the provision of more than two supporting legs renders it stiff and practically non-collapsible, even by the weight of workmen walking over the same before the concrete is 85 poured.

I claim:

1. The combination of a bar, a supporting chair carried by said bar, said chair having a plurality of legs formed by folding the 90 metal upon itself into M-shape, all of which legs are apertured for the passage of the bar, said legs being disposed diagonally with respect to each other and frictionally held to the bar in adjusted positions by the inherent resiliency thereof, in combination with reinforcing bars supported by the chair - carrying bars and lying between the folded portions of the legs of said support.

2. The combination of a bar, a series of 100 sheet metal supporting chairs having a plurality of legs formed by folding the metal upon itself and being substantially M-shaped in cross section carried by said bar, each of said legs being apertured whereby 105 such support may be strung on a bar, said legs being disposed at an angle with respect to each other so that the natural resiliency

of the metal will tend to frictionally clamp the chair to the bar, in combination with reinforcing bars confined between the folded portions of the legs of said chair and resting upon the bar supporting said chair, and means on the supporting bar for maintaining said chairs in definite position with respect to the same.

In testimony whereof, I have signed my name to this specification, in the presence of 10 two subscribing witnesses.

DANIEL A. WEDMORE.
